Primary Examiner—Cathron B. Matta
Attorney, Agent, or Firm—Richard B. O'Planick

[57] **CLAIM**

The ornamental design for a lid for food container, as shown and described.

DESCRIPTION

FIG. 1 is a top right front perspective view of a lid for food container showing our new design;
 FIG. 2 is a top plan view thereof;
 FIG. 3 is a front elevational view thereof; the rear elevational view being a mirror image;
 FIG. 4 is a bottom plan view thereof; and,
 FIG. 5 is a right side elevational view thereof; the left side elevational view being a mirror image.
